UNITED STATES PATENT OFFICE.

JOHN WHITEHEAD WILSON DRYSDALE AND JOHN YOUNG, OF YOKER, NEAR GLASGOW, SCOTLAND, ASSIGNEES TO DRYSDALE & COMPANY, LIMITED, OF YOKER, NEAR GLASGOW, SCOTLAND.

CENTRIFUGAL PUMP.

Application filed November 3, 1923. Serial No. 672,573.

To all whom it may concern:

Be it known that we, JOHN WHITEHEAD WILSON DRYSDALE and JOHN YOUNG, both subjects of the King of Great Britain and Ireland, both residing at Bon-Accord Works, Ferry Road, Yoker, near Glasgow, Scotland, have invented certain new and useful Improvements in Centrifugal Pumps; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to centrifugal pumps and is intended to be applied to pumps employed for the withdrawal of liquid from vessels under high vacua such as surface and jet condensers, vacuum evaporators, and the like, wherein the condensed vapour or liquid is withdrawn from the lowest point of the vessel and pumped to any desired pressure above atmosphere.

The satisfactory working of a centrifugal pump under such conditions is the object of the present invention. For satisfactory working it is necessary to secure freedom from air leakage at glands, a self-clearing action in regard to air locks, and the maintenance of a head of water over the impeller eye. With regard to the last point, it is often difficult under the conditions in question to secure any considerable head for the pump; and the ability of the pump to work with a low head is therefore of great importance.

With the object aforesaid in view the pump in accordance with the present invention is arranged to rotate on a vertical shaft. It is of the two-stage type, i. e. with two impellers in series. The first-stage impeller is disposed at the lowest point in the pump, and is so arranged that the water from the vessel which is being drained or drawn from, tends to gravitate into the eye of this impeller. The water passages of the pump are so disposed as to prevent the formation of air locks by the flow in the said passages being always upwards from the first-stage im-

peller to the final discharge outlet of the pump.

A feature of advantage in the present invention is the provision of a chamber situated above the first-stage impeller and in communication with the eye of this impeller, and connected by means of a balance pipe to the vessel which is being drained or drawn from, the intention being that air drawn by the liquid from the said vessel shall be caught in the chamber and drawn back into the said vessel by the air pump which is employed for withdrawing air from the vessel.

Further features of advantage of our invention are an annular nozzle or passage situated at and above the eye of the first-stage impeller and an air-extraction duct connecting the chamber above-mentioned with this annular nozzle or passage, the object being the extraction, by way of the annular nozzle or passage, the chamber, and the balance pipe, of any air which collects by vortex action at the eye of the impeller.

In the carrying of the present invention into effect the first-stage impeller—situated at the lowest point in the pump—is arranged to deal with the water at low absolute pressure and to discharge this water to the second-stage impeller which is situated above the first-stage impeller, which second-stage impeller raises the pressure of the water to any desired amount. This two-stage arrangement has the advantage that the pressure at the eye of the second-stage impeller may be, and in practice preferably is, arranged to be above atmosphere, thus tending to prevent air leakage into the pump.

The accompanying drawings illustrate the carrying of the invention into effect in one convenient manner.

Fig. 1 is a vertical section through the pump.

Fig. 2 is a horizontal section on the line A A of Fig. 1.

Fig. 3 is a front elevation drawn to a reduced scale.

The pump casing is constructed split in a vertical plane passing through the axis of rotation, thus allowing of the ready removal of the rotating parts without disturb-

ing pipe joints. The split is clearly shown in Fig. 2 and the difference in cross hatching in Fig. 1 makes clear the two parts into which the casing is divided, while the jointing is shown in Fig. 3.

5 *a* is the first-stage impeller and *b* the second-stage impeller. The discharge from the first-stage impeller to the second-stage impeller is by way of the duct *e* in the pump 10 casing, which duct leads in an upwards and radially-inward direction from the volute or discharge chamber of the first-stage impeller to the eye of the second-stage impeller (which is on the lower side of this 15 impeller), there being no openings, glands, or the like, in this duct which would allow of the induction of air.

20 The discharge from the volute *g* of the second-stage impeller to the discharge chamber *f* of the pump is by way of the port *h*, indicated by shading in Fig. 2.

25 The discharge chamber *f* is arranged to surround the shaft where the latter enters the pump casing at the top thereof, the pressure of water discharge thus effectually sealing or packing the pump against air leakage (which may be occasioned by the 30 improper adjustment of the packing gland). *d*, *d* are the two discharge ports either of which may be employed.

35 *c* is the suction port of the pump. This is connected by the pipe *p* to the vessel which is being drained or drawn from. The port *c* is continued by the passage or chamber *k* above and communicating with the eye of the first-stage impeller, which is on the upper side of this impeller.

40 The locations of the two impellers and the positions of their eyes—one at the top of the impeller and the other at the bottom—is of great importance in the prevention of air locks.

45 *t* is a chamber situated above the suction port and in communication therewith. It is also placed in communication with the vessel which is being drained or drawn from by means of a balance pipe *q*. The object of the chamber *t* with the balance pipe is that air drawn in by the liquid from the said 50 vessel shall be caught in the chamber and drawn back into the said vessel by the air pump which is employed for withdrawing air from the vessel.

55 *r* is an annular nozzle or passage which projects into the eye of the first-stage impeller and leads upwards to the chamber *u* which by means of the duct *v* communicates with the chamber *t*. The object of the nozzle

60 and duct is the extraction of any air which collects by vortex action at the eye of the impeller. This air rises through the duct *v* and passes away by the pipe *q*.

65 If the vacuum in the vessel which is being drained or drawn from is not constant throughout, it is desirable that the pipe *q* be led to that part or place in the vessel at which the highest vacuum exists.

What we claim is:—

70 1. A centrifugal pump comprising a casing, a vertically arranged shaft mounted therein, a first-stage impeller located at the bottom of said casing, a second-stage impeller located above said first-stage impeller, said impellers each having radially extending discharge openings and being jointly connected to said shaft, said first-stage impeller having an eye located at the top thereof, said second-stage impeller having an eye located at the bottom thereof, and means of communication extending in an upward and 75 radially inward direction between the discharge openings of the first-stage impeller and the eye of the second-stage impeller.

80 2. A centrifugal pump having a vertical axis of rotation and comprising a first-stage impeller located at the bottom of the pump, the eye of this impeller being at the top thereof, a second-stage impeller located above the said first-stage impeller, the eye of this impeller being at the bottom thereof, 85 a chamber located above the said first-stage impeller and in communication with the eye of this impeller, and a balance pipe connecting the said chamber with the vessel which is being drained or drawn from.

90 3. A centrifugal pump having a vertical axis of rotation and comprising a first-stage impeller located at the bottom of the pump, the eye of this impeller being at the top thereof, a second-stage impeller located 95 above the said first-stage impeller, the eye of this impeller being at the bottom thereof, a chamber located above the said first-stage impeller and in communication with the eye of this impeller, a balance pipe connecting the said chamber with the vessel which is being drained or drawn from, an annular 100 passage located at the eye of the said first-stage impeller and leading upwards therefrom, and a duct leading from the said 105 passage to the said chamber.

110 We hereby sign our names to this specification.

JOHN WHITEHEAD WILSON DRYSDALE.
JOHN YOUNG.
